UNITED STATES PATENT OFFICE

1,934,016

PASTE TUBE CAP

Adam J. Strehs, Miami, Fla.

Application May 5, 1932. Serial No. 609,476

4 Claims. (Cl. 221—60)

This invention relates to certain new and useful improvements in paste tube cap.

The primary object of the invention is to provide a cap for paste tubes of the character disclosed in application for patent filed by Adam J. Strehs on May 2, 1932, Serial Number 608,771 and embodies a simplified construction of closure means for the discharge nozzle of the tube confined within the cap and operated during inward and outward movement of the cap on the tube neck to be shifted to opened and closed positions relative to the discharge nozzle.

A further object of the invention is to provide a cap for paste tubes of the foregoing character wherein the closure means or valve for the discharge nozzle of the tube is carried by the underside of the top wall of the cap to be shifted to opened or closed positions relative to the discharge nozzle of the tube by means carried by the tube neck and associated therewith.

With the above and other objects in view that will become apparent as the nature of the invention is better understood, the same consists in the novel form, combination and arrangement 25 of parts hereinafter more fully described, shown in the accompanying drawing and claimed.

In the drawing:—

Figure 1 is an upper end elevational view of the assembled tube and cap with the valve device 30 in closed position relative to the discharge nozzle of the tube;

Figure 2 is a fragmentary side elevational view of the tube with the cap shown in section and illustrating the cap and closure valve for the discharge nozzle in closed position;

Figure 3 is an upper end elevational view of the assembled tube and cap with the cap and valve device in open position, the latter being shifted laterally of the discharge nozzle of the 40 tube;

Figure 4 is a fragmentary side elevational view of the tube and cap shown in section and in its open position with the discharge nozzle of the tube projected through an opening in the top wall of the cap;

Figure 5 is a horizontal sectional view taken on line 5—5 of Figure 2;

Figure 6 is a horizontal sectional view taken 50 on line 6—6 of Figure 4;

Figure 7 is a side elevational view of the valve device for the discharge nozzle of the tube removed from the tube cap; and

Figure 8 is an enlarged fragmentary side 55 elevational view of the upper end of the tube,

showing the slot formation therein for guiding the cap in movements over the tube neck;

Referring more in detail to the accompanying drawing, the reference numeral 10 designates a container for viscous substances such as tooth paste, dental or shaving cream, or similar substances, the container 10 being preferably in the form of a collapsible tube that is closed at one end and carrying at its other end a rigid neck portion 11 from which a discharge nozzle 12 that is open at its outer end centrally projects. Diametrically opposite sides of the tube neck 11 are provided with inclined or cam grooves 13 merging at their outer ends into relatively short annular groove portions 14, the 60 terminal ends of which groove portions 14 are inclined inwardly or toward the tube 10 as at 15.

The cap for the tube is associated with the tube neck 11 and includes a top wall 16 carrying an annular skirt or flange 17 that carries at its free edge diametrically opposite inwardly directed lugs 18 working in cam and groove portions 13, 14 and 15 as will at once be obvious from an inspection of Figures 2 and 4. The top wall 16 of the cap is provided with a central opening 19 through which the open end of the discharge nozzle 12 is adapted to be projected when the cap is moved to an open position as shown in Figure 4.

A closure valve is provided for the discharge nozzle 12 and is confined within the tube cap, being carried by the under face of the top wall 16 of the cap and automatically operated by means carried by the tube neck upon operation 90 of the cap to be shifted to open and closed positions relative to the discharge nozzle. The closure valve for the discharge nozzle includes a plate or arm of the configuration best illustrated in Figures 5 and 6, having an intermediate portion 20, parallel perpendicularly extending walls 21 and 22, the free end of the wall 21 carrying an outwardly directed flange 23 while the free end of the wall 22 carries an outwardly directed valve plate 24, the flange 23 and valve plate 24 being disposed in the same plane and in wiping contact with the underside of the top wall 16 of the cap with the intermediate portion 20 thereof spaced from the cap and retained in such position by the pivot pin 25 in the top wall of the cap. The intermediate portion 20 of the valve device is provided with a curved cam slot 26 having the end thereof adjacent the wall 21 of the valve device laterally directed as at 27 for purposes 100 105 110

presently to appear. The perpendicular pin 28 rising from the upper face of the tube neck 11 entering the slot 26.

When the cap is disposed at its limit of outward movement relative to the tube neck 11, the same is in closed position with the plate valve 24 of the valve device overlying the open outer end of the discharge nozzle 12 and being disposed inwardly of the opening 19 in the top wall 16 of the cap. To place the cap and valve plate 24 in closed position, the lugs 18 carried by the cap flanges 17 move upwardly through the cam portions 13 of the neck slot and through the relatively short annular portions 14 thereof and when the lugs 18 reach the forward ends of the annular slot portions 14, the pin 28 is disposed in the end of the slot 26 adjacent the wall 21 of the valve arm. Further movement of the cap in the direction of closing movement thereof outwardly of the neck 11 causes the lugs 18 of the cap to move downwardly or inwardly through the inclined portions 15 of the neck groove, the valve device remaining immovable but carried slightly inwardly with the cap to cause binding engagement thereof on the open outer end of the discharge nozzle 12. To move the cap and valve device to open position, the cap is moved inwardly upon the tube neck 11 to the position illustrated in Figures 4 and 6, the cap lugs 18 travelling through the groove portions 14 and 13 in the neck, while the cam slot 26 in the intermediate portion 20 of the valve arm causes a lateral swinging movement of the valve arm by the presence of the pin 28 extending into the cam slot so that the valve plate 24 is shifted laterally of the discharge nozzle 12 to assume the position shown in Figure 6 and at which time the discharge nozzle 12 is projected through the opening 19 of the top wall of the cap for the free discharge of the contents of the tube therethrough. When moving the cap and valve device to closed position with respect to the discharge nozzle 12, the cap is moved outwardly of the tube neck 11, being guided in its movement by the cam groove 13 and annular groove portions 14, the pin 28 and cam slot 26 being so related one to the other to cause the valve plate 24 of the valve device to overlie the discharge nozzle 12 when the cap is at its limit of outward movement, continued movement of the cap in the same direction causing a slight inward movement thereof upon the neck 11 occasioned by the inclined portion 15 of the neck groove for more securely sealing the outlet of the discharge nozzle. It will be noted that the valve device is positively moved from open to closed positions relative to the discharge nozzle as contrasted with spring or resilient devices and that the tube closure is of extremely simple construction embodying comparatively few parts and is capable of inexpensive manufacture, as well as being of a highly sanitary character and protecting the contents of the tube.

70

75

While there is herein shown and described the preferred embodiment of the invention, it is nevertheless to be understood that minor changes may be made therein without departing from the spirit and scope of the invention as claimed. 80

I claim:

1. In a receptacle closure, a receptacle having a neck and discharge nozzle, cam grooves in the neck, a cap having side lugs working in the cam grooves and a top opening through which the nozzle is adapted to be projected, a valve plate pivotally mounted within the cap to overlie the nozzle, and means carried by the neck and cooperating with the valve plate to move the same to open and closed positions relative to the nozzle upon movements of the cap on the neck. 85

2. In a receptacle closure, a receptacle having a neck and discharge nozzle, cam grooves in the neck, a cap having side lugs working in the cam grooves and a top opening through which the nozzle is adapted to be projected, a valve plate pivotally mounted within the cap to overlie the nozzle, and means carried by the neck and cooperating with the valve plate to move the same to open and closed positions relative to the nozzle upon movements of the cap on the neck, including a pin rising from the neck and the valve plate spaced upwardly of the neck and having a cam slot therein into which the pin 90 extends whereby upon movement of the cap inwardly and outwardly of the neck the valve plate is laterally shifted relative to the nozzle. 95

3. In a collapsible tube, a tube having a neck and discharge nozzle rising centrally of the neck, 100 said neck having cam grooves therein and a pin rising from the neck laterally of the nozzle, a cap having lugs working in the cam groove and a top opening aligned with the nozzle and through which the nozzle is adapted to be projected, and 115 a valve plate pivotally mounted on the underside of the cover and having a cam slot therein into which the pin extends for moving the valve plate relative to the nozzle upon rotative inward and outward movement of the cap on the tube 120 neck. 110

4. In a collapsible tube, a tube having a neck and discharge nozzle rising centrally of the neck, 125 said neck having cam grooves therein and a pin rising from the neck laterally of the nozzle, a cap having lugs working in the cam groove and a top opening aligned with the nozzle and through which the nozzle is adapted to be projected, a valve plate pivotally mounted on the underside of the cover and having a cam slot therein into 130 which the pin extends for moving the valve plate relative to the nozzle upon rotative inward and outward movement of the cap on the tube neck, the end of the valve plate opposite the pivot adapted to overlie the discharge nozzle and the intermediate portion of the valve plate being spaced from the top wall of the cap to permit passage of the pin through the cam slot. 135
